(57) CLAIM

The ornamental design for a gaming desk as shown and described.

DESCRIPTION

FIG. 1 is a perspective view of a gaming desk showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 1;

FIG. 11 is an enlarged view of portion 11 shown in FIG. 1;

FIG. 12 is an enlarged view of portion 12 shown in FIG. 1;

FIG. 13 is an enlarged view of portion 13 shown in FIG. 1;

FIG. 14 is an enlarged view of portion 14 shown in FIG. 2;

FIG. 15 is an enlarged view of portion 15 shown in FIG. 2;

FIG. 16 is an enlarged view of portion 16 shown in FIG. 2;

FIG. 17 is an enlarged view of portion 17 shown in FIG. 2;

and,

FIG. 18 is an enlarged view of portion 18 shown in FIG. 8. The broken lines in the drawings depict portions of the gaming desk that form no part of the claimed design.

The dash dot dash broken lines encircling claimed subject matter depict the boundaries of the enlarged views and form no part of the claim.

1 Claim, 18 Drawing Sheets
